UNITED STATES PATENT OFFICE.

JULIUS VASSIE WILSON, OF HIGH POINT, NORTH CAROLINA, ASSIGNOR TO LUCY K. WILSON, OF HIGH POINT, NORTH CAROLINA.

CONVERTIBLE FURNITURE.

Application filed March 29, 1928. Serial No. 265,694.

The present invention relates to convertible furniture, preferably of the type known as "davenport", which can be extended to form a bed. The object is to provide a novel structure by which the sections that make up the bed structure are more compactly folded within the lower portion of the davenport frame.

A further and important object is to provide a structure in which the sections are very effectively supported and held in their extended relation so that the danger of collapse is avoided.

In the accompanying drawings:

15 Figure 1 is a longitudinal sectional view through the preferred embodiment of the invention, showing the frame-work in its extended relation to constitute a bed,

20 Figure 2 is a similar view, but with the structure folded to produce a davenport.

Figure 3 is a view with the parts partially folded or unfolded.

Figure 4 is a detail perspective view of one of the supports for the head section 25 when in its operative position.

Figure 5 is a detail side elevation of one of the foot section holding hooks.

Figure 6 is an end elevation of the same.

Figure 7 is a detail perspective view of 30 one of the connections of the spring fabric with the body section.

In the embodiment disclosed, a main frame 8 is provided, including end pieces 9, having suitable arms 10 and a back wall 11. 35 A swinging back frame 12 is pivoted, as shown at 13, to the end walls and can be swung between an operative position, as shown in Figure 2 and to a position out of the way, as illustrated in Figures 1 and 3. 40 It will be understood that these frames can be finished and upholstered in any manner desired.

The bed structure comprises three sections. A body section 14 is pivoted at its 45 rear end and as shown at 15 to the front end portion of the main frame 8. It comprises an open frame with end bars 16 and cross bars 17, said frame constituting a seat structure for the davenport when folded within 50 the main frame in a manner well understood. The end bars 16, it will be noted, have widened end portions 18 and 19, which are

upwardly extended when the seat member is in its extended position as illustrated in Figure 1. A head section 20 is provided, comprising end bars 21 connected at their rear ends by a cross bar 22, and having their other ends wider, as shown at 23, and adapted to abut against the inner widened end 18 55 of the body section. Said portions 18 and 23 are connected by hinges 24. Obviously with this arrangement, when the body section 14 is swung into the main frame 8, the head section will be lowered, as shown in Figure 2, and when said body section 14 is 60 swung outwardly, the head section will be raised, as illustrated in Figure 1.

In order to firmly support the head section when thus raised and at the same time 70 permit it to lower, two supports are provided. Each of these supports consists of an upper link 25 and a lower link 26 pivoted together, as shown at 27, the upper link being pivoted at its upper end, and as illustrated at 28, to one end bar 21 of the body

frame 20, the lower link being pivoted between its ends, as shown at 26' to the lower portion of an end wall 9 of the main frame. The lower link 26 terminates at its lower 80 end in an offset ear 29, to which is connected a rearwardly extending coiled spring 30, secured, as shown at 31, to the rear portion of the main frame. In addition there is an abutment head 32 carried by the end bar 21 85 of the head section 20 and so disposed that when the head section lowers, as indicated in Figure 3, it will cause the links 25 and 26, which are in alined position, as shown in Figure 1, to swing rearwardly against the action of the spring 30. Consequently as the body section 14 is swung on to the head section 20, said head section will be pressed down against the action of the springs and said springs are put under additional tension by being extended to assist in raising the head section when the body section is again swung outwardly.

In swinging outwardly moreover at a certain point, the springs 30 will cause the head section to assume a position where the outer ends of the end bars 21 will abut squarely against the end bar 16 of the body section and this abutting action is firmly maintained by the 90

There is also provided a foot section 33, comprising end bars 34 connected at their outer ends by a cross bar 35 and having their inner ends enlarged, as shown at 36, and 5 coacting with the enlarged ends 19 of the end bars 16 of the body section 14. These end portions 19 and 36 are connected on their upper ends by hinges 37 so that obviously the foot section will swing between a folded 10 position on the body section and an extended position in alignment therewith and with the end portions 19 and 36 squarely abutted as illustrated in Figure 1. For the purpose of firmly supporting the outer end of the 15 body section 14, legs 38 are fixed thereto and are connected by a cross piece 39 and braces 40 are preferably employed for said legs 38. In like manner, provision is made for firmly supporting the foot section 33. This is ac- 20 complished by means of legs 41 pivoted at their upper ends and as shown at 42 to the end bars 34 of said foot section 33. The legs 41 have their lower ends pivotally connected as shown at 43 to links 44 that are pivoted 25 as illustrated at 45 to the fixed legs 38. Con-sequently when the foot section is swung to its folded position, the legs 41 will be swung until they assume a position alongside the end bars 34, as illustrated in Figure 3. To 30 hold the foot section in its folded position on the body section, hooks 46 are pivoted as shown at 47 on the enlarged portions 18 of the end bars 16 of the body section and engage over the free end of said foot sec- 35 tion, as illustrated in Figures 1, 2 and 3.

In this structure, a spring fabric constituting the bed bottom is provided. This may be the usual link construction and is shown at 48, so that it is readily flexible. Its side 35 edges are secured by coiled springs 49 to angle irons 50 fastened to the various end bars 16, 21 and 34 of the different sections. Its end edges are connected by coiled springs 51 to the rear cross bar 22 of the head sec- 40 tion 20 and the outer cross bar 35 of the foot section 33, so that it is always under trans-verse tension and is also under longitudinal tension when the bed is extended as shown in Figure 1. When so extended, it will be 45 noted that the spring fabric is located at a point below the axes of the hinges 24 and 37, thus firmly holding the ends of the vari-ous side bars in abutting relation. More than that, the line on which the outer end 50 portion of the fabric swings when the foot section is swung (which line is indicated at A in Figure 1), is by reason of the connec-tion of the springs 49 below and in rear of the axis of movement of the foot section. 55 The result is that there is a "dead center" created by the "pull" of the springs 51 when the foot section is swung that causes the raising of said section to be resisted until a certain point is reached, whereupon the foot 60 section can be easily swung to its folded po-

sition. This same resistance of course occurs on the opening movement until the dead center is passed, whereupon the springs pull the foot section to its fully open position and maintain it in such position.

From the foregoing, it is thought that the construction, operation and many ad-vantages of the herein described invention will be apparent to those skilled in the art, without further description and it will be 75 understood that various changes in the size, shape, proportion and minor details of con-struction may be resorted to without depart-ing from the spirit or sacrificing any of the 80 advantages of the invention.

What I claim is:

1. In a folding structure of the character described, the combination with a main frame, of a body section pivotally mounted thereon, a head section pivoted to the body section and located within the frame, a folding support for the head section comprising links pivoted together and to the frame and head section, said links swinging to folded position when the body section is 90 swung to a position over the head section and thereby lowering the head section, and re-versely swinging to supporting relation and permitting the elevation of the head section when the body is swung outwardly from over 95 the head section and an abutment carried by the head section and pressing against the up-per link in the lowering movement of the head section to relatively swing the links to folded position.

2. In a folding structure of the character described, the combination with a main frame, of a body section pivotally mounted thereon, a head section pivoted to the body section and located within the frame and a folding support for the head section comprising links pivoted together and to the frame and head section, said links swinging to folded position when the body section is 105 swung to a position over the head section and thereby lowering the head section, and re-versely swinging to supporting relation and permitting the elevation of the head section when the body is swung outwardly 110 from over the head section, a spring con-nected to one of the links at one side of its pivot mounting for causing their relative movement in one direction on a correspond-ing movement of the head section, and means 115 for causing the links to relatively move in 120 an opposite direction on the corresponding movement of the head section.

3. In a folding structure of the character described, the combination with a main frame, of a body section pivotally mounted 125 thereon, a head section pivoted to the body section and located within the frame, and a folding support for the head section comprising upper and lower links pivoted to-gether and to the frame and head section, 130

said links swinging to folded position when the body section is swung to a position over the head section and thereby lowering the head section, and reversely swinging to supporting relation and permitting the elevation of the head section when the body is swung outwardly from over the head section, a spring connected to the lower link at one side of its pivot mounting for causing their relative movement in one direction on a corresponding movement of the head section and an abutment on the head section and engaging the upper link for causing the links to relatively move in an opposite direction on the corresponding movement of the head section.

4. In a folding structure of the character described, the combination with a main frame, of a body section pivoted at one end

and below the upper side of the section to 20 the front side of the main frame, a head section hinged to the body section above the said pivotal connection and having a rising and falling movement in the frame upon the swinging movement of the body section, 25 sets of supporting links for the head section, each set comprising pivotally connected upper and lower links, the lower links being pivoted between their ends to the frame, springs engaged with the lower ends of the 30 lower links, the upper links being pivoted to the head section, and abutments on the head section that engage the upper links and cause the links during falling motion of the head section, to relatively swing against the action of the springs.

In testimony whereof, I affix my signature.
JULIUS VASSIE WILSON.
